UNITED STATES PATENT OFFICE.

BYRON W. SECHRIST, OF READING, PENNSYLVANIA.

WARP-OPERATED SHUTTLE ATTACHMENT.

Application filed May 9, 1923, Serial No. 637,731.

To all whom it may concern:

Be it known that I, BYRON W. SECHRIST, a citizen of the United States, residing at Reading, in the county of Berks and State of Pennsylvania, have invented certain new and useful Improvements in Warp-Operated Shuttle Attachments, of which the following is a specification.

My invention relates to loom-shuttle attachments for automatically putting into action the usual stop mechanism of the loom by breaking of the bobbin thread; and it consists in an improved attachment adapted to be automatically operated for such purpose by the warp threads in case the latter form a defective shed for the passage of the shuttle. The invention is fully set forth in connection with the accompanying drawings and clearly defined in the subjoined claim.

Fig. 1 is an enlarged partial plan-view of an ordinary loom shuttle, showing an edge view of my applied attachment with the thread-cutting blade projected to part the deflected bobbin thread.

Fig. 2 shows an inner-face view of the attachment with the blade in normal retracted position; the shuttle being indicated in cross-section on the line 2—2 of Fig. 1.

The shuttle A is provided as usual with a bobbin B carried on a suitable spindle in the longitudinal recess C of the shuttle; the bobbin thread b extending through a guide eye D at the forward end of the extended recess. My improved attachment is secured to the inner side wall of the recess beyond the end of the bobbin, as shown; so that the breaker-blade 10 thereof, when projected in a horizontal plane as hereinafter described, will deflect the feeding bobbin thread against the opposing wall plate 11 of the recess, as indicated by the full line b in Fig. 1 and so effect the breaking or cutting of said thread and the consequent stoppage of the loom.

My improved attachment provides for automatically effecting this projection of the breaker-blade 10 to break the bobbin thread b, by action thereon of any warp-threads which, through entanglement or other cause, may obstruct the free passing of the shuttle in the shed; the purpose being to promptly stop the loom for correction of the trouble before defective fabric is produced.

To this end my improved attachment provides a blade-actuating mechanism which comprises a trigger-lever having a warp-thread-contacting arm 12 forming an arcu-

ate projection above the casing 13 of the attachment and the top surface of the shuttle; so as to insure operating contact thereof with any warp-threads which may obstruct the free passage of the shuttle. As shown this arcuate trigger-lever is pivotally mounted at 12^a between the front and rear casing plates 13^a, 13^b, and is formed with a depending tripping extension 12^b which is pressed against by an adjustable spring 14 so as to normally hold the arcuate arm 12 at a determined projection through the top of the casing, with the extremity stopped against a casing shoulder 13^c. This tripping extension 12^b of the trigger lever bears against one arm of a bell-crank latch lever which is pivoted to the casing at 21 so that its angled arm 22 will be swung in a vertical plane by action of the trigger lever, with the adjustable spring 14 also acting thereon. The breaker blade 10, which is pivoted upon a vertical casing-post 10^a as indicated, is provided with a catch 23 adapted to be retainingly engaged normally by the latch arm 22, but is constantly pressed upon by any suitable blade-projecting spring 24 operative to swing it horizontally when the latch 22 is released by deflection of the warp-operated trigger lever 12; such swinging movement of the blade 10 pressing the bent bobbin thread b against the opposite wall surface 11 of the recess so as to effect the cutting or breakage of said thread and consequent stoppage of the loom.

Because of the limited pressure which is exertable by the tangled warp threads upon the trigger lever 12, and the jars to which the movable parts are subjected by the frequent sudden stoppages of the shuttle, the several features of construction as set forth cooperate to insure such reliable operation as is essential for practical use; the normally positioned arcuate trigger lever 12 being directly and effectively operated by any contacting warp-threads so as to positively disengage the latch arm 22 from the blade catch device 23, while accidental disengagement thereof is prevented by the arrangement of its swing at right angles to that of the blade and by the engaging pressure of the adjustable spring 14; and the released breaker blade being effectively swung by its spring 24 so as to press the deflected bobbin-thread against the opposite wall of the shuttle recess. The preferred specific structure may obviously be modified within

the scope of the invention as defined in the claim.

What I claim is:

In combination with a loom shuttle having a bobbin spindle and recess therefor, a warp-operated bobbin thread-breaker device comprising a casing fixed to the recess wall and arranged forwardly of the cop-spindle, a thread-breaker blade pivotally connected 10 to said casing and normally arranged at one side of the axis of the spindle, an anvil plate located in the recess opposite said casing and at the opposite side of said axis, a spring

urging said blade toward said anvil plate, a bell-crank lever pivoted to swing in a plane 15 at right angles to the plane of movement of the blade, a spring normally forcing said lever into contact with the blade to permit the lever to hold said blade in the casing, and a second pivotally mounted arcuate 20 lever engaging the bell-crank lever and projecting beyond the shuttle for engagement by the warp threads in the loom.

In testimony whereof I affix my signature.

BYRON W. SECHRIST.
